UNITED STATES PATENT OFFICE.

GEORGE A. ARNDT, OF CHICAGO, ILLINOIS, ASSIGNOR TO EMIL G. JOHANSON, OF CHICAGO, ILLINOIS.

DESIGN FOR A HEADLIGHT-REFLECTOR.

58,455.

Specification for Design.

Patented July 26, 1921.

Application filed October 14, 1919. Serial No. 330,615. Term of patent 7 years.

To all whom it may concern:

Be it known that I, GEORGE A. ARNDT, a citizen of the United States, residing at Chicago, in the county of Cook and State of Illinois, have invented a new, original, and ornamental Design for a Headlight-Reflector, of which the following is a specification, reference being had to the accompanying drawing, in which—

Figure 1 is a plan view of the design; and Fig. 2 is a cross-section thereof.

I claim:—

The ornamental design for a headlight reflector as shown.

In testimony whereof I affix my signature.

GEO. A. ARNDT.
